UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

PRINTING-MACHINE.

1,209,409.

Specification of Letters Patent. Patented Dec. 19, 1916.

Application filed July 29, 1912. Serial No. 711,979.

To all whom it may concern:

Be it known that I, JOSEPH S. DUNCAN, a citizen of the United States, residing at Chicago, in the county of Cook and State of Illinois, have invented certain new and useful Improvements in Printing-Machines, of which the following is a specification.

This invention relates in general to printing machines and has for its primary object the provision of a machine adapted to print at one printing operation a complete circular letter including the address and the salutation.

Another object of the invention is the provision of novel means whereby a different address is presented at each printing operation and whereby the proper salutation required by each address, such as "Dear Sir", "Gentlemen", or "Dear Madam", is automatically provided.

A further object of the invention resides in the utilization of a common inking ribbon through which the body of the letter, the address and the salutation are simultaneously printed, thereby eliminating the distinctions between the address, salutation and body of the letter which are readily apparent when the body of a letter and the address and salutation are printed from different ribbons.

Still another object is to secure a uniform and equal platen pressure upon each printing character of the letter body, address and salutation, so that the entire letter will present uniform and equally distinct character impressions closely simulating typewritten matter.

Another object is to provide means whereby the pressure of the platen may be regulated and also means whereby the length of the effective stroke of the platen may be regulated, as required.

Other objects and advantages of the present invention and many novel features of construction will be recognized as the details of one preferred embodiment thereof become better understood by reference to the following description when considered in connection with the accompanying drawings.

Referring to the drawings—Figure 1 is a plan view of a printing machine embodying my invention, a portion of the machine at the feed end being broken away; Fig. 2 is a front elevation looking toward the delivery end of the machine shown in Fig. 1;

Fig. 3 is a similar view looking toward the feed end of the machine shown in Fig. 1; Fig. 4 is a side elevation looking toward the right at Fig. 1; Fig. 5 is a transverse sectional view taken on the line 5—5 of Fig. 4; Fig. 6 is a plan view of the machine with certain parts removed, said view being taken substantially on the line 6—6 of Fig. 5; Fig. 7 is a longitudinal sectional view through the machine, taken substantially on the line 7—7 of Fig. 6; Fig. 8 is an enlarged fragmentary plan view showing the salutation forms and mechanism for operating the same; Fig. 9 is an elevational view looking toward the left in Fig. 8, certain parts of the machine being omitted; Fig. 9^a is a perspective view of a section of the address from carrier track; Fig. 10 is a view taken substantially on the line 10—10 of Fig. 6; Fig. 11 is an enlarged fragmentary view of the intermittently operated connection between the drive shaft and the platen operating lever; Fig. 12 is a view looking toward the left in Fig. 11; Fig. 13 is a fragmentary view of one of the platen track adjusting devices; Fig. 14 is a view looking toward the left in Fig. 13; Fig. 15 is a view taken on the line 15—15 of Fig. 5; Fig. 16 is a sectional view taken on the line 16—16 of Fig. 15; Fig. 17 is a detail perspective view of one section of the platen track; Fig. 18 is a perspective view of an address form; Fig. 19 is an enlarged fragmentary sectional view taken through the stationary printing form, the address form and a salutation form; Fig. 20 is a perspective view of the track upon which the salutation forms slide; Fig. 21 shows a detail of the stationary printing form; Fig. 22 is a fragmentary perspective view of the stationary form bed; Fig. 23 is a detail of the sliding bar connecting the various salutation forms; Fig. 24 shows the face of the address form bed; Fig. 25 is a detail view showing a salutation form typeholder; and Fig. 26 is a detail view showing one of the typeholders with which the stationary form bed is equipped.

The machine shown on the drawings as illustrative of one practical embodiment of my invention is designed to print at each operation a complete form letter including the address and salutation and to automatically change the address at each operation and, also, automatically present the particular salutation required by the address

being printed. To this end the machine includes a stationary form bed upon which the body of the letter is set up, a plurality of address forms which are stored in a magazine and fed consecutively to printing position and, also, a plurality of salutation forms with mechanism controlled from the address forms to present the required salutation form at each printing operation. A single inking ribbon is employed through which the address, salutation and body of the letter are printed, thereby insuring uniform and homogeneous impressions from all of the forms. A single platen is mounted to travel across the forms and produce an impression simultaneously from the stationary, the address and the salutation forms, the platen being operated in the present instance by novel mechanism which causes it to travel alternately in opposite directions across the form and to print during its movement in each direction. Suitable mechanism is also employed for regulating the platen pressure and also for regulating the length of the effective platen stroke. The details of construction, however, of the mechanism briefly mentioned are capable, as will be readily apparent when the invention is better understood, of considerable variation in structure and operation without departing from the essence of the present invention.

By reference now to the drawings, it will be observed that the various mechanisms are carried by a main frame 31 supported upon suitable pedestals or feet and shaped or proportioned in accordance with the requirements of the mechanisms mounted thereon. The top of the frame is adapted to receive and support a suitable stationary printing form bed 32 (Figs. 5 and 8) which is equipped with type to provide the form from which the body of the letter is printed. Referring to Figs. 19, 22 and 26 it will be seen that the base of the bed 32 is provided on its upper face with a series of transversely extending parallel grooves 33 in which are arranged T-shaped type-holder bars 34 spaced apart a sufficient distance to permit the individual type 35 to be slid into position between them. The type may be of any preferred construction, but, in the present instance, I have shown them as provided with undercut grooves at each side to receive the flanges of the holding bars and so proportioned that the type will be positioned as closely together as the individual impressions and lines of impressions are in ordinary typewritten matter. It will be understood that the structure of the stationary bed may be varied as desired and that it may, if preferred, be made of sheet metal with the printing characters stamped up therefrom. The number of lines of type and the subject matter represented thereby will, of course,

be determined by the character of the letter to be printed in any particular instance.

Address printing mechanism.—The address forms 36, which are employed to provide various addresses to the body of the letter produced by the stationary printing form, are arranged in a suitable magazine 37 at one side of the machine, as shown in Figs. 3, 5 and 6. One of the address forms is shown on an enlarged scale in Fig. 18, from which it will be observed that a sheet metal body is provided with suitable open-ended slots 38 into which the type 39 are inserted in the usual manner and held in position by slugs, or otherwise. The ends of the address form, or printing device, as it is frequently termed, are preferably bent downwardly and then inwardly as indicated at 41, thereby forming spacing and supporting flanges to prevent injury to the faces of the type when the devices are stacked in the magazine.

The address forms may be conveyed consecutively from the magazine to printing position adjacent the stationary printing form by any suitable mechanism, one practical construction, however, consisting of an endless chain conveyer 42 and a movable bed 43, (Fig. 5). The conveyer as shown comprises a pair of chains trained around suitable sprocket wheels 44 and 45, the upper travel of the chains being disposed directly beneath the magazine 37 so that the address forms may drop thereon, one at a time. The conveyer is equipped at intervals with projecting members 46 adapted to engage with the rear edge of the lowermost address form in the magazine, whereupon the form is carried forward by an intermittent motion of the conveyer into position directly above the bed 43 as shown in Fig. 10. Suitable stationary tracks or guideways 47 support the upper travel of the conveyer and, also, maintain the address forms in proper position thereon. The sprocket wheel 45 is mounted in a suitable bearing 48 (Figs. 5 and 6) which may be adjusted by an adjusting screw 49 to regulate the tension of the chains. An intermittent motion is imparted to the conveyer by means of a Geneva stop motion which comprises a radially grooved member 51 fixed to the shaft 52 on which the sprocket wheels 44 are mounted and a roller 53 (Figs. 3 and 6) carried by a gear wheel 54 mounted on a shaft 50 and driven from a gear wheel 55 on the shaft 56 which shaft, in turn, is driven through the intermediary of the bevel gears 57 from the main drive shaft 58 which may be actuated by the handle 59 or by power derived from any suitable source. The roller 53 is adapted to engage in one of the radial grooves of the member 51 and impart a quarter turn to the shaft 52 at each revolution of the gear 54. A suitable stop plate 61 on the face of the gear 54 is adapted to hold the shaft 52 against rotation between

its successive operations by the roller 53. The conveyer driving mechanism is timed to operate between the successive printing operations and as the address forms are carried 5 consecutively from the magazine they are positioned directly over the movable bed 43. The movable bed 43 is next operated to elevate the address form positioned thereover above the conveyer and into printing position 10 with its printing face in alinement with the printing face of the stationary form.

The bed 43 is provided on its upper face with a series of ribs 62 (Figs. 19 and 24) adapted to engage with the body of a printing device 36 between adjacent lines of type to form a rigid and substantial support for the address form during the printing operation. The bed is mounted upon a frame 63 (Figs. 5, 8 and 10) which is provided at 15 each side with rollers 64 resting upon and supported by cams 65 on the shaft 56. A link 66, pivoted at one end at 67 to the bed frame and at 68 to the frame of the machine and a similar link 69 pivoted at 71 to 20 the lower end of the bed frame 63 and at its other end at 72 to the main frame of the machine, serves to guide the bed frame in its up and down movements and retain the same at all times in a substantially vertical position 25 so that the upper face of the bed 43 is maintained in horizontal position. The cams 65 are so shaped and proportioned that when the conveyer is moving, the upper face of the bed 43 will be disposed beneath 30 the path of travel of the address forms on the conveyer and when the conveyer stops, the bed will be elevated sufficiently to raise the particular address form disposed thereover into printing position in alinement with 35 the stationary form 32.

In order to hold the address form in proper position on the bed and to prevent displacement of the form during the printing operation, I have mounted a clamping plate 73 at each side of the conveyer on a post 74 which, in turn, is slidably mounted in perforated studs 75 and 76 fixed to extensions of the frame 63. A coiled expansion spring 77 surrounding each post presses 40 against the stud 76 at one end and a pin 78 at the other end passes through the post 74. This spring normally holds the clamping plate 73 down against the track 47 which is cut away at this point as indicated at 45 (Fig. 9^a) to permit the top of the clamping plate to lie flush with the top of the tracks, but sufficiently above the path of travel of the address forms 36 to permit them to travel freely along the tracks (as shown in 50 Fig. 10). When the bed 43, however, raises the address form off from the conveyer the ends of the form are brought into engagement with the clamping plates 73 which hold the form tightly against the face of 55 the bed and prevent the form from becoming

displaced. Sufficient clearance is provided between the stud 76 and the plate 73 to enable the bed to be brought into engagement with the address form before the plates are raised. When the bed has been 60 elevated a predetermined distance the stud 76 is brought into engagement with the plate, or, if preferred, the parts may be so proportioned that the stud 75 will be brought into engagement with the pin 78, 65 whereupon the bed, the address form and the clamping devices will all travel upwardly together without further relative movement between them. Upon lowering the bed it will be understood that the address form is deposited on the conveyer, the clamping plates are sustained above the form by the tracks 47 and the bed proper travels downwardly a sufficient distance to 70 permit the form to be carried along without interference upon the next actuation of the conveyer. After the address form has been again deposited on the carrier by the movable bed, subsequent to the printing operation, it is delivered by movement of the 75 carrier over a guide or separator 79 (Fig. 5) into a drawer, or other receptacle 81, supported in an inclined position on a table or trough 82. The trough is pivotally carried intermediate its ends in a stirrup 83 so that 80 the rear end may be lowered to permit removal of the drawer 81, whereupon the drawer with the address forms contained therein may be stored for future use, or the forms may be returned directly to the magazine 37. A retarder 84 co-operating with a 85 movable packer 85 operated by a well known means (not shown) serves to maintain the address forms in compact relation to each other as they are delivered in succession to 90 the drawer.

Salutation printing mechanism.—In the present machine the salutation is printed simultaneously with the address and the body of the letter and, in order to provide 95 the proper salutation to each address I have equipped the machine with three independent salutation printing forms adapted to print "Dear Sir", "Gentlemen" and "Dear Madam", respectively. The forms in themselves may be of any preferred construction stamped up from sheet metal, or composed of individual type assembled in a holder. In the present instance, however, I have chosen to illustrate the salutation forms as 100 consisting each of a suitable holder 86 (Figs. 19 and 25) grooved on its upper surface to receive the type 87 which are formed to fit snugly in the grooves of the holder. These holders with the type therein are 105 mounted in alinement upon a suitable track 88 extending parallel with the lines of type on the stationary and address forms and mounted at each end upon the main frame 110 31 of the machine, as shown in Figs. 6 and 115 130

8, the track being screwed or bolted to the frame in the required position, as shown. By referring more particularly to Fig. 20 it will be seen that the track or bar 88 is provided intermediate its ends with an elevated portion 89 which, in practice, is formed immediately beneath the position where it is desired to print the salutation on the letter. The sides of the typeholders 86 are extended downwardly as shown in Figs. 19 and 25 to straddle the track 88. Each holder 86 is provided on one side with an aperture 91 and a bar or slide 92 is equipped on one side with projecting studs 93 each adapted to engage in an aperture 91 of a holder as shown in Fig. 10. These studs fit loosely in the apertures in the holders so that the holders may move upwardly relatively to the bar as they ride over the high portion 89 of the track. The bar is moved longitudinally to bring the required form over the high portion of the track by mechanism which will be hereinafter described. In Fig. 10 the middle holder is shown as resting on the high portion of the track so that the printing characters are elevated into printing position and in alinement with the printing characters of the stationary form and the address form. The track is provided with a groove 94 (Fig. 20) in which the lower edge of the bar is guided and a lateral groove 95 is also provided to accommodate the ends of the studs 93. In order to obtain the requisite spacing between the salutation and the first line of the body of the letter, it is desirable that the first line of type of the stationary form be positioned close to the salutation forms. To this end a member 96 is bolted or otherwise secured to the edge of the form bed 32, which member is equipped with a groove 97 to receive the base of the type and provide a holder therefor, and is also provided with an overhanging shoulder 98 beneath which the bar 92 slides. It will thus be seen that the sliding bar is guided in its reciprocal movements by the member 96 and the track 88 and it will be manifest that by simply moving the bar back and forth the required salutation form may be shifted onto the elevation 89 of the track and thereby presented to printing position. The upward movement of the form bed 43 brings the address form close to the salutation form so that when the printing operation takes place the address, salutation and the first line of the body of the letter will all be spaced apart the requisite distance. The movement of the bar 92 to bring the required salutation form into printing position is preferably controlled from the address forms, themselves, which have certain structural characteristics adapted, through the coöperation therewith of certain mechanisms, to cause a salutation form, cor-

responding with the address form to be printed, to be presented to printing position. Various different structural characteristics of the address forms might be selected to accomplish this result and suitable mechanism be designed to coöperate therewith. In the present instance, however, I have disclosed one practical and efficient manner of controlling the salutation forms from the address forms which will now be described. A link 99 is connected at one end with the sliding bar 92 and at its other end to an oscillatory member 101 adapted to oscillate in both directions beyond the central position shown in Figs. 8, 9 and 10. The oscillation of this member is controlled by a feeler 102 pivoted at 103 on an extension 104 of the movable bed frame 63, which feeler, dependent upon the extent of its movement permitted by the particular address form subjected to detection, causes the oscillatory member to move in one direction or the other from neutral position. To the upper arm of the feeler there is pivotally mounted at 105 a pair of rigidly connected feeler fingers 106 and 107, respectively, differing in length as shown in Fig. 8. A coiled tension spring 108 secured at 109 to the bed frame 63 and at 111 to a lateral arm of the feeler normally tends to urge the fingers toward the left (Fig. 10) into engagement with the address form 36 positioned above the movable bed 43. A fixed pin 112 projecting from the main frame of the machine holds the feeler in retracted position when the bed frame 63 is in lowered position. When the bed moves upwardly, however, carrying with it the feeler pivot the spring 108 rocks the feeler about its pivot to project the fingers toward the address form being raised, the track 47 being cut away as indicated at 110 (Fig. 9a) to permit projection of the feeler fingers into engagement with the form. The address forms requiring different salutations are characterized by a predetermined number of perforations 113 provided in the ends of the forms as shown in Fig. 9. Some of the forms have one perforation, some two and some none, and, obviously, the extent of movement of the feeler about its pivot will depend upon the number of perforations. If, for instance, the particular form being detected is provided with no perforations the end of the longer feeler finger 107 will abut against the end of the form and thereby prevent any operative movement of the feeler about its pivot. If the form is provided with one perforation the longer feeler finger will pass through the perforation and the movement of the feeler will be limited by engagement of the end of the shorter finger with the end of the form. If two perforations are present in the form being detected both fingers will protrude through 130

the perforations and the maximum movement of the feeler will be permitted. In this way the extent of movement of the feeler is automatically controlled by the address forms.

The oscillatory member 101 has a widened base as shown in Fig. 10, one end of which is pivotally connected by a bolt 114 with a stirrup 115 normally supported upon the frame 31 of the machine, the bolt 114 having a projecting end extending over the slide 125. A pin or rod 116 projects downwardly through and fits relatively loosely in a boss on the machine frame, thus affording a sliding connection between the stirrup and the frame which permits the stirrup to be raised without being disconnected from the frame. A similar stirrup 117 is spaced from the stirrup 115 a distance substantially equal to the width of the base of the oscillatory member and is likewise slidably connected with a boss 120 on the frame 31 by a pin or rod 118. In order to permit the oscillatory member to oscillate without binding the pins 116 and 118 in their bosses, a link 119 is employed to effect a connection between the oscillatory member and the stirrup 117. This link is pivoted by a bolt 121 to the base of the oscillatory member and by a pin or bolt 122 to the stirrup 117, the bolt 122 having a projecting end extending over the slide 125 similarly to the bolt 114. A spring 123 connected at one end with the machine frame and at its other end with the oscillatory member normally holds said member in the neutral position shown. The bed frame 63 is provided with an integral lateral extension 124 which projects adjacent to the stirrups 115 and 117. The slide 125 is mounted in a guiding groove formed in the face of the extension 124 and is held in operative position therein by a clip 100 secured to the face of the extension. The inner end of the slide is provided with a perforation into which extends the lower end 126 of the feeler 102. The slide is provided adjacent its outer end with two notches 127 and 128 best shown in Fig. 8.

In the position of the parts shown the notch 127 is in alinement with the pin or bolt 114 and when the bed frame is elevated, carrying with it the slide, the notch enables the slide to pass the pin 114 without engaging therewith and the oscillatory member 55 remains in neutral position with the salutation "Gentlemen" in printing position. Should an address form provided with one perforation 113 be presented for detection by the feeler the feeler will move about its 60 pivot, as previously explained, until the end of the shorter finger 106 engages the end of the form. This movement will cause the slide 125 to move outwardly a sufficient distance to bring that portion of the slide between the notches 127 and 128 directly be-

neath the pin 114. Upon upward movement of the bed frame the slide will engage with the pin and carry the pin upwardly with it, thereby oscillating the member 101 to the right, viewing Fig. 10, about the pin 122 as a pivot. The address forms will, therefore, be moved to the right and the salutation "Dear Madam" will be presented to printing position. Should an address form provided with two perforations be presented for detection a maximum movement of the feeler about its pivot will be permitted, as previously explained, and the notch 128 will be moved to position directly beneath the pin 114. The end of the slide, however, beyond the notch 127 will be positioned beneath the pin 122 and upon the upward movement of the bed frame this portion of the slide will engage the pin 122, thereby carrying it upward and oscillating the member 101 to the left about the pin 114 as a pivot. This movement will slide the salutation forms bodily to the left and present the salutation "Dear Sir" to printing position. It will thus be seen that with the mechanism disclosed the required salutation form will be presented to printing position at each printing operation without any care or adjustment by the operator. According to the present disclosure the address requiring the salutation "Gentlemen" is set up in a form having no perforations; that requiring the salutation "Dear Madam" is set up in a form having one perforation and that requiring the salutation "Dear Sir" is set up in a form provided with two perforations. Obviously, however, this order might readily be changed by simply changing the relative positions of the salutation printing forms on the slide bar 92 and other salutations other than those mentioned above might be employed, if so desired.

Paper feeding mechanism.—The paper is fed through the machine from left to right, viewing Fig. 4, and is held in position over the printing forms during the printing operation by mechanism which will now be described. The main frame of the machine is provided with a rearwardly extending bracket or projection 130 (Figs. 4 and 7) in which is journaled a shaft 129. A sheave 131 fixed on said shaft is connected by a belt 132 with a sheave 133 fixed on the drive shaft 58, whereby a continuous rotary movement is imparted to the shaft 129. Pulleys 134 and 135 are fastened on the shaft by set screws which may be loosened to permit adjustment of the pulleys longitudinally of the shaft for the accommodation of paper of different widths when required. At the opposite end of the machine (Figs. 2 and 6) are mounted a pair of shafts 136 and 137 carrying pulleys 138 and 139, respectively, which are likewise adjustable on these shafts to aline with the pulleys 134 and 135 at the

opposite end of the machine. Tapes 141 and 142 are trained over the pulleys and extend across the machine adjacent the printing forms. From Fig. 5 it will be observed that 5 the upper travels of the tapes are disposed just above the printing forms while the lower travels run beneath the forms. The stationary form bed 32 is preferably provided with grooves 143 on its lower face to 10 permit transverse adjustment of the tape 142. Idle pulleys 144 and 145 are mounted on shafts 146 and 147, respectively, at the delivery end of the machine over which the tapes travel and similar idlers 148 (Fig. 7) 15 are adapted to guide the tapes at the feed end of the machine. In order to maintain the tapes under the requisite tension a belt 20 tightener in the form of a pulley 149 is carried at the extremity of arms 151 pivoted on the shaft of the roller 148 so that the weight 25 of the pulley 149 is sustained by the tapes. The tapes are continuously operated, as before stated, and the paper is deposited upon them at the feed or left end, viewing Fig. 7 either by hand or any suitable feeding device.

For the purpose of stopping the paper in printing position over the forms, I have provided suitable stops against which the 30 forward edge of the paper abuts. These stops designated by 152 (Figs. 1 and 7) are mounted on arms 153 fixed to a rock shaft 154 extending transversely of the machine. The stops may be adjusted longitudinally 35 of the arms 153 so that when the arms are in the elevated position, as shown, the forward edge of the paper will abut against them and the paper will be stopped in proper position for printing. To prevent 40 the feeding of more than one piece of paper onto the printing form at one time, I have provided a plurality of preliminary stops 155 (Figs. 1 and 7) mounted on rods 156 secured to a rock shaft 157, which stops 45 are also adapted to be elevated into the path of the paper. The shafts 154 and 157 are connected by a link 158 so that the two shafts are rocked synchronously to raise and lower all of the stops simultaneously. 50 An operating arm 159 extends from the shaft 157 over cam 161 fixed on the shaft 55. At each revolution of the shaft the stops are lowered below the path of travel of the paper to permit the sheet already 55 printed to be delivered at the rear of the machine and to permit the sheet being held by the stop 155 to progress to printing position. The stops are then elevated into position shown in Fig. 7 to prevent further 60 movement of the paper until after the next printing operation. From the foregoing it will be understood that the paper is fed intermittently by continuously moving tapes and is retarded at intervals in its travel by 65 stops interposed in its path.

Inking mechanism.—In the present machine the impressions are taken through a single inking ribbon which extends over the stationary, the salutation and the address forms. This inking ribbon 162, as shown 70 in Fig. 5, is fastened at each end to suitable ribbon rolls 163 and 164, respectively. These rolls are mounted in the main frame of the machine and are operated to feed the ribbon forward after each printing operation 75 by means of mechanism best disclosed in Fig. 2. Referring to this figure it will be seen that each ribbon roll shaft is equipped with a ratchet wheel 165 and that a lever or link 166 on one shaft is connected 80 with a similar lever 167 on the other shaft by a link 168. A pawl 169 is pivoted at the end of the link 168 and is held in operative relation with the ratchet wheel 165 by a spring 171. The spring also holds the pawl 85 in inoperative position when turned on its pivot against a stop on the link 166 so that the spring pulls on the opposite side of the pivot and against the stop. A similar pawl 172 is mounted at the other end of the link 90 168 and is held in operative or inoperative position by a spring 173. A link 174 is connected at one end with one arm of the lever 167 and at its other end encircles an eccentric 175 on the shaft 56. At each revolution of the shaft a reciprocatory movement will be imparted to the pawls 169 and 172 and the inking ribbon will be fed in one direction or the other, depending upon which of the pawls is in operative engagement with its ratchet wheel. When the ribbon 95 has been entirely fed through the machine the pawls may be reversed to cause the ribbon to be fed back in the other direction. By employing a single inking ribbon 100 through which the impressions are taken simultaneously from the stationary form, the address form and the salutation form, a much more uniform or homogeneous letter will be produced than would be possible 105 where the body of the letter, the address and salutation are printed through different ribbons. The advantages of a single ribbon both in the character of the work produced and in the simplicity of mechanism 110 will be readily apparent.

Platen operating mechanism.—The paper is pressed against the inking ribbon superimposed upon the printing forms by a platen of any suitable construction. In the present instance, however, I employ a rotatable cylindrical platen 176 which is caused to travel, by novel operating mechanism, back and forth across the forms lengthwise of the lines of type. The platen is guided in its movements across the form between suitable tracks mounted on adjustable brackets 177 and 178 which tracks 120 co-operate with guide rollers 179 and 181 mounted at the ends of the platen. Bear- 125

ing blocks 182 are mounted on the ends of the platen shaft and each block is connected with an endless chain 183 (Figs. 4 and 7). Suitable sprocket wheels 184 and 185 are 5 mounted on the machine frame and the chains 183 are trained around them, the sprocket wheels being so arranged that the pull upon the platen is exerted in a right line substantially parallel with the faces of 10 the printing form. A bell-crank lever 186 is pivoted at 187 to the main frame of the machine and the long arm of the lever is connected by a link 188 with the lower travel of one of the chains 183. When the 15 lever is oscillated about its pivot the chain will be moved back and forth and this motion will also be imparted to the other chain through the shaft 189 (Fig. 6) to which both of the sprocket wheels 185 are fixed. 20 The mechanism for operating the bell-crank lever 186 is best shown in Figs. 3, 7, 11 and 12. Referring to these figures it will be observed that a collar 191 is loosely mounted on the inner end of the shaft 58 25 and that one end of the collar is connected with the short arm of the bell-crank lever by means of a link 192. An arm 193 is fixed to the shaft 58 adjacent this collar and carries at its outer end a pivotally mounted 30 dog 194. The collar is provided on its inner face with a pair of studs 195 and 196 and, a tension spring 197 connected at 198 with the dog 194 and at its other end with a pin 199 fixed to the arm 193, tends normally to urge the dog into engagement with the studs. A fixed pin 201 projects from the bracket 200 supporting the shaft 58 into the path of the tail of the dog 194, so that as the shaft 58 revolves the dog will be prevented from engaging with the stud 196 40 (Fig. 11), but will be released after passing that stud and drawn by the spring 197 into position to engage the stud 195 after the dog has completed a half revolution. Engagement 45 of the dog with the stud 195 will cause the collar 191 to turn with the shaft 58 through half a revolution, at which time the engagement between the dog and the stud will be broken by engagement of the 50 tail of the dog with the pin 201. The collar will then remain stationary until the shaft has completed the other half revolution, whereupon the dog will be brought into engagement with the stud 196 which is then in uppermost position. It will be obvious, 55 therefore, that each revolution of the shaft 58 causes a half revolution of the collar 191. The bell-crank lever 186 is thereby oscillated to move the platen alternately in opposite directions across the printing form. It will be seen, therefore, that the various 60 mechanisms are so timed and arranged that the platen will make only one excursion across the printing form at each complete cycle of the machine and, as the result, the

platen prints one sheet while traveling across the form in one direction and prints the next sheet while traveling across the form in the opposite direction, thus obviating the return of the platen to neutral 70 position after each printing operation.

Referring now more particularly to Figs. 5, 7, 15 and 16, it will be observed that the rollers 179 travel beneath the tracks 202 mounted on the overhanging portions of the brackets 177 and 178. These tracks hold the platen down in operative relation to the printing form. For the purpose of regulating the effective stroke of the platen I prefer to make the track 202 in two sections, 75 one of which is shown in Fig. 17, adapted to overlap. These sections are positioned in undercut grooves in the brackets 177 and 178 and are held in position by plates 203 fastened to the brackets by screws 204, or 80 other suitable means. If long lines are to be printed the track sections are extended the required distance in opposite directions by simply loosening the plates 203, thereby increasing the distance within which the 85 platen will be held against the form. When shorter lines are to be printed it is desirable to shorten the tracks 202, accordingly, so that pressure will not be exerted upon the ribbon beyond the ends of lines which might 90 cause smudging of the paper.

The platen is yieldingly urged upwardly against the tracks 202 by lower tracks 205 positioned to engage with the rollers 181. These tracks, as best shown in Figs. 15 and 16, are yieldingly supported by leaf springs 206, the upward movement of the tracks being limited by bolts or screws 207 connecting the tracks with the brackets 177 and 178. These tracks are adapted to support the weight of the platen and when the rollers 179 travel off the ends of the tracks 202 the platen is sustained and slightly elevated, thereby obviating any danger of pressing the paper against the ribbon to cause 100 smudging. From an inspection of Fig. 15 it will be observed that the ends of the track 205 are curved upwardly as indicated at 200. This upward curvature is provided to positively lift the platen a limited distance 105 above the paper, thereby permitting the paper to be freely fed into and from printing position. The platen is, therefore, caused to travel in a right line in operative relation to the printing form during the length of 110 its effective stroke and at the completion of its stroke in each direction it is positively elevated out of engagement with the paper so that no obstruction will be offered to the 115 feeding movements of the paper.

Platen pressure regulating mechanism.—The brackets 177 and 178 upon which the guiding tracks for the platen are mounted are adjustable on the main frame so that the pressure of the platen against the print- 120

ing form may be regulated as occasion requires. By reference to Figs. 1 to 7, inclusive, it will be seen that the brackets extend downwardly at each side of the main frame of the machine and are adjustably supported at their lower ends. The weight of the brackets is partially carried by bolts 208 passing through apertures in extensions 209 of the main frame and yieldingly supported by expansion springs 211. Upward travel of the bolts is limited by lock-nuts 212 (Fig. 14). The brackets 177 and 178 are provided near their lower ends with bearings to receive shafts 213 which, at each end, are provided with eccentrically disposed pintles 214 projecting into bearing blocks 215 fixed to the main frame. It will be obvious that by turning the shafts 213 in the blocks 215 the brackets will be raised or lowered a limited amount.

In order to secure uniform and homogeneous impressions throughout the surface of the sheet being printed, it is essential that the platen pressure be equally distributed from end to end of the platen; therefore, it is necessary that both ends of the platen be adjusted an equal amount. I have accordingly mounted upon each of the shafts 213, as shown in Fig. 6, an arm 210 and have connected these arms by a rod 220. Any rocking movement of one of the shafts will, therefore, be imparted to the other so that the brackets 177 and 178 will be adjusted equally. For the purpose of rocking the shafts to effect the adjustment I have provided a threaded link 216 attached at one end to the adjacent arm 210 and passing through bracket 217 fixed to the main frame. A hand wheel 218 having threaded engagement with the rod 216 is rotatably connected with the bracket, the wheel, however, being held against longitudinal movement by a bearing plate 219 engaging with a collar 221 fixed to the hub of the wheel. Upon rotation of the wheel in one direction or the other, the rod 216 will be moved longitudinally to rock the shafts 213, thereby effecting a vertical adjustment of the brackets 177 and 178, whereby the requisite platen pressure is obtained. The spring-pressed bolts 208 serve to relieve the bearings of the weight of the brackets without interfering with their adjusting movements. The platen pressure may, by the mechanism disclosed, be regulated to a fine degree of nicety and uniform impressions of the desired character may be produced at each printing operation.

Operation.—In the operation of the embodiment of my invention as disclosed the paper is fed to printing position from one end of the machine, the address forms are fed consecutively to printing position from the side of the machine and the required salutation form is presented to printing posi-

tion in accordance with the particular characteristic of the address form to be printed. The platen is then rolled across the forms above the paper, pressing the paper against the inking ribbon so that an impression of all the form characters is produced. The platen is then elevated into inoperative position, the address form is deposited on the conveyer and delivered to the storage drawer or tray, the inking ribbon is fed forward a step, the printed sheet is delivered at the rear of the machine and a fresh sheet is presented to printing position, whereupon the printing operation is repeated. The platen, however, travels this time in the opposite direction. The various adjustments hereinbefore described may be made as occasion requires, but after the parts have been initially adjusted very little attention need be given to the machine. By the employment of this invention form letters including the address and the required salutation can be printed with great rapidity and accuracy and the printed sheets will so closely approach typewritten matter in appearance that they can not be readily distinguished by the ordinary observer.

It is believed that my invention will be understood from the foregoing without further description and, while I have shown and described one practical embodiment of the invention, it will be obvious that the details of construction are capable of considerable modification without departure from the essence and scope of the invention as set forth in the following claims.

I claim:

1. In a printing machine, the combination of a stationary letter form, a magazine, a plurality of address forms arranged in said magazine, means including a reciprocatory frame for moving said address forms consecutively to printing position, a plurality of salutation forms, means carried by said frame and controlled by the address forms for selecting and positioning the required salutation form in printing position, a rotatable platen, and automatic means for operating said platen after the forms have been properly positioned to cause the printing of the letter, address and salutation at one operation of the platen.

2. In a printing machine, the combination of a stationary form, a magazine, a plurality of address forms disposed in said magazine, a movable form bed, means for conveying said address forms consecutively from the magazine to the bed, means for elevating the bed to align an address form with the stationary form, a plurality of salutation forms, and means controlled by the address forms for positioning the desired salutation form in alignment with said stationary and address forms.

3. In a printing machine, the combination

- of a magazine, a plurality of printing devices disposed therein, a movable bed, a plurality of links pivotally connected to the bed frame and to the main frame of the machine for guiding said bed during its movement, an intermittently operated conveyer adapted to convey the address forms consecutively from the magazine to position over said bed, mechanism for elevating said bed whereby to lift an address form from the conveyer into printing position, a plurality of salutation forms, and means for alining a selected one of said salutation forms with said address form in printing position. 15
4. In a printing machine, the combination of a stationary printing form, a plurality of salutation forms, means for reciprocating said salutation forms transversely of the stationary form, and means dependent upon the position of the salutation forms for elevating one of said forms during its travel in either direction into alinement with the face of the stationary form. 20
5. In a printing machine, the combination of a stationary form, a plurality of salutation forms arranged in alinement adjacent the stationary form, means for imparting a reciprocatory movement to all of said salutation forms simultaneously, and means for elevating one of said salutation forms relatively to the others and into alinement wth the face of the stationary form. 25
6. In a printing machine, the combination of a printing form, a slide movable transversely of said form, a plurality of salutation forms connected with said slide, and means adapted to engage with a salutation form upon movement of the slide to elevate said form relatively to the remaining salutation forms and into printing position. 30
7. In a printing machine, the combination of a plurality of address forms, means for elevating said forms successively into printing position, a plurality of salutation forms, mechanism actuated by said address form elevating means for moving a desired salutation form into printing position, and means controlled by an address form for establishing a coöperative relation between said elevating means and said mechanism. 35
8. In a printing machine, the combination of a plurality of address forms, means for elevating said forms consecutively into printing position, a plurality of salutation forms, mechanism adapted to be operated from said elevating means for moving a desired salutation form into printing position, a feeler adapted to contact with an address form, and means controlled by said feeler for establishing a connection between said address form elevating means and said salutation form positioning means. 40
9. In a printing machine, the combination of a plurality of address forms, means for moving said forms into printing position, a plurality of salutation forms, mechanism for moving a desired salutation form into printing position including a slide and an oscillating member connected thereto, a pivotally mounted feeler adapted to contact with each address form as it approaches printing position, and a feeler controlled member adapted to effect the connection between the oscillating member and said address form moving means, whereby the movement of the address form into printing position causes the simultaneous movement of the required salutation form into printing position. 45
10. In a printing machine, the combination of a plurality of salutation forms, a slide loosely connected with each of said forms, means for reciprocating said slide, and a stationary cam mounted in the path of travel of the forms for moving said forms individually into printing position. 50
11. In a printing machine, the combination of a track, a plurality of salutation forms mounted to reciprocate thereon, said track being provided with an elevated portion adapted to move a form into printing position, a slide connected with each of said forms, an oscillating member connected with said slide, and means for oscillating said member to bring the required salutation form into printing position. 55
12. In a printing machine, the combination of a plurality of salutation forms, an oscillatory member connected with said forms, a reciprocatory device mounted to reciprocate adjacent said oscillatory member, means for causing said oscillatory member to be operated by said reciprocatory device, and stationary means for elevating a salutation device into printing position upon oscillatory movement of said member. 60
13. In a printing machine, the combination of a reciprocatory bed, means for delivering address forms successively to the bed, means for elevating said bed to dispose an address form carried thereby in printing position, a plurality of salutation forms, an oscillatory member connected therewith, a feeler, means for moving said feeler into detecting position during elevation of the bed, and means controlled by the feeler for operating said oscillatory member upon movement of the bed, whereby to shift the required salutation form into printing position. 65
14. In a printing machine, the combination of a vertically movable bed, means for delivering address forms thereto, means for elevating said bed to dispose a form carried thereby in printing position, a movable feeler carried by the bed comprising a plurality of fingers, means for yieldingly urging said feeler toward said form, the travel 70

of said feeler being determined by the structural character of the form on the bed, a plurality of salutation forms, and means dependent upon the extent of movement of the 5 feeler for positioning the required salutation form in printing position.

15. In a printing machine, the combination of a plurality of address forms, means including a vertically reciprocable bed for 10 moving said address forms into printing position, a plurality of salutation forms, and means dependent upon the character of the particular address form on the bed for moving the required salutation form into printing position, said means comprising a feeler having a plurality of relatively immovable fingers pivotally mounted on said bed and mechanism connecting the feeler and the salutation forms for positioning said forms 15 in accordance with the extent of movement 20 of said feeler.

16. In a printing machine, the combination of a plurality of printing forms having different structural characteristics, a movable 25 feeler having a plurality of rigidly connected fingers adapted to detect the different characteristics of various forms, and means for urging said feeler into detecting position, the relation of said different structural characteristics of the printing forms 30 to said fingers being such that the absence of one of said characteristics causes the corresponding finger to act as a stop to prevent further movement of said feeler.

35. 17. In a printing machine, the combination of a plurality of printing devices having different structural characteristics, a movable feeler comprising a plurality of rigidly 40 connected fingers adapted to detect the different characteristics of various devices, means controlled by the feeler for presenting the salutation "Dear Sir:" "Gentlemen:" or "Dear Madam:" to printing position in conformity with the indicated requirements 45 of any particular printing device, and means for urging said feeler into detecting position, the relation of said different structural characteristics of the printing forms to said fingers being such that the absence of one of 50 said characteristics causes the corresponding finger to act as a stop to prevent further movement of said feeler.

18. In a printing machine, the combination of a bed, means for moving a printing 55 device into juxtaposition to said bed, means for elevating the bed into engagement with the device, and means carried by the bed normally above the path of movement of and out of engagement with said printing 60 device adapted to engage with the upper face of the device and clamp the same against the bed upon elevation of the bed into engagement with the device.

65. 19. In a printing machine, the combination of a reciprocatory bed, a printing de-

vice, means for positioning said device in juxtaposition to the bed, means for moving said bed into engagement with the device, and means normally disposed above the path of movement of the device across the 70 bed but constructed to move conjointly with and relatively to the bed, whereby said means is brought into contact with the upper face of the device upon upward movement of the bed, to clamp said device to the face 75 of the bed.

20. In a printing machine, the combination of a magazine, a plurality of printing devices disposed therein, a reciprocatory bed, means for moving the devices consecutively from the magazine to a position adjacent to the bed, means for moving the bed into engagement with the devices, and automatic means carried by the bed normally above the path of a device delivered thereto 80 from the magazine but movable relatively to the bed upon upward movement of said bed whereby to engage and hold said device against the face of the bed.

21. In a printing machine, the combination of a magazine, a plurality of printing devices disposed therein, a reciprocatory bed, a carrier for conveying the devices consecutively from said magazine to the bed, means for elevating the bed to lift a device from 90 the carrier, and means comprising a plurality of clamping members disposed above the path of travel of said device across the bed to permit a device to be fed to the bed and movable relatively to the bed to engage 100 and hold a device against the face of the bed when in elevated position.

22. In a printing machine, the combination of a plurality of printing devices, a track, a carrier movable thereon and adapted to carry the printing devices in spaced relation, a pair of clamping members normally disposed above the printing devices on the carrier, a reciprocatory bed adapted to elevate a printing device above the carrier, and means for yieldingly depressing said clamping members to hold the device against the face of the bed when in elevated position.

23. In a printing machine, the combination of a stationary printing form, a plurality of interchangeable address forms, a plurality of interchangeable salutation forms, means including an oscillatory device and a pair of rigid feeler fingers for presenting to printing position the salutation form required by any particular address form, a common inking ribbon through which the impression is made from each of said forms, a platen for causing an impression to be 115 taken at one operation from each of the forms, and means for feeding the inking ribbon forward after each printing operation.

24. In a printing machine, the combina- 130

- tion of a rotatable platen, means for causing the platen to travel transversely of its axis alternately in opposite directions, yielding means for moving the platen into inoperative 5 position at each end of its stroke, rigid means for positively maintaining said platen in operative position between its limits of travel, and means for varying the operative length of the platen stroke.
- 10 25. In a printing machine, the combination of a printing form, a platen, means for moving said platen across the form alternately in opposite directions, means for holding the platen in coöperative relation 15 to the form during a portion of its stroke there-across, means whereby the operative portion of the platen stroke may be varied, and means for separating the platen from the form at each end of the operative portion 20 of the stroke.
26. In a printing machine, the combination of a printing form, a rotary platen, an endless chain carrier connected with said platen, a continuously rotating shaft, a dog 25 carried by said shaft, a collar provided with a plurality of studs, connections between said collar and said carrier, and means controlling said dog to intermittently connect said collar with the shaft whereby an intermittent movement in opposite directions 30 is imparted to the platen carrying conveyer.
27. In a printing machine, the combination of a continuously rotating shaft, a collar loosely mounted thereon, studs on said collar, a dog carried by the shaft, means for causing said dog to intermittently engage with said studs in alternation, a bell-crank lever, a platen connected to one end of said lever, and a link connected at one end to said 35 collar and at its other end to said bell-crank lever whereby the platen is moved alternately in opposite directions from the continuously rotating shaft.
28. In a printing machine, the combination of a shaft, a dog carried thereby, a collar provided with studs loosely mounted on said shaft, a link connected to said collar, a bell-crank lever having one arm attached to said link, an endless chain connected to the 40 other arm of said lever, a rotatable platen, guides therefor, and means for causing said dog to intermittently and alternately engage with said studs whereby to impart a right line movement to the platen alternately in opposite directions.
29. In a printing machine, the combination of a stationary printing form, a plurality of address forms, means including a reciprocatory bed for presenting said address forms consecutively to printing position, a plurality of salutation forms, means including a multiple finger feeler adapted to contact with the address forms for presenting the required salutation form to 45 printing position, an inking ribbon disposed over said forms, a rotatable platen, and means for imparting a right line movement to said platen across the forms whereby an impression through said ribbon is procured at one operation from the stationary form, 50 address form and corresponding salutation form.
30. In a printing machine, the combination of a printing form, a rotatable platen, means for imparting a right line movement 55 to said platen alternately in opposite directions, rollers mounted at the ends of the platen, tracks for pressing said platen against the printing form, means for simultaneously adjusting the tracks at both ends 60 of the platen equally throughout their entire length whereby to regulate the pressure of the platen uniformly throughout its stroke, and means whereby the length of the tracks may be varied.
31. In a printing machine, the combination of a rotatable platen, a printing form, means for rolling said platen across said printing form, a track at each end of the platen for pressing the platen against the 65 form, and means for simultaneously adjusting the position of said tracks to regulate the pressure of the platen, said means comprising a plurality of shafts and a manually operated adjusting device for simultaneously 70 actuating said shafts.
32. In a printing machine, the combination of a platen, rollers mounted at the ends thereof, tracks disposed above the rollers to retain the platen in operative position, means for urging said rollers against the tracks, means whereby the length of the tracks may be adjusted to regulate the length of the operative stroke of the platen, and means for simultaneously adjusting the 75 tracks equally throughout their lengths to regulate the platen pressure.
33. In a printing machine, the combination of a printing form, a reciprocatory bar, a plurality of salutation forms loosely connected with said bar, and means for imparting a conjoint movement to said salutation forms through the intermediary of the bar and an independent movement to one of said forms relatively to the bar.
34. In a printing machine, the combination of a printing form, an address form, a plurality of salutation forms, means for moving said salutation forms conjointly, and means for moving one of said salutation 85 forms independently of the others.
35. In a printing machine, the combination of a plurality of salutation forms, means for reciprocating said forms conjointly, and means adapted upon reciprocatory movement of said forms in either direction to move a selected one of said forms transversely to the conjoint direction of travel.
36. In a printing machine, the combina- 90

tion of a stationary printing form bearing a plurality of lines of type, a magazine adapted to support a plurality of changeable printing forms, means for successively feeding changeable printing forms from said magazine to a position adjacent said stationary printing form, an inking ribbon, means for feeding said ribbon longitudinally of said stationary printing form, and a platen

10
roller movable transversely of said stationary printing form and in the direction of the lines of type thereon to cause an impression to be taken through said ribbon from said printing forms.

JOSEPH S. DUNCAN.
